(57) **CLAIM**

The ornamental design for embossed paper, as shown and described.

DESCRIPTION

FIG. 1 is a legend diagramming the location of fragmented FIGS. 1A and 1B;

FIG. 1A is a fragmented plan view of embossed paper showing the new design;

FIG. 1B is a fragmented plan view thereof;

FIG. 2 is an enlarged fragmentary sectional view thereof taken substantially along line 2—2 of FIG. 1A; and,

FIG. 3 is an enlarged fragmentary sectional view thereof taken substantially along line 3—3 of FIG. 1B.

It is to be understood that FIGS. 1A and 1B represent broken-away fragments as indicated by the breakaway lines present in each fragmentary plan view.
